WELL EQUIPMENT

Wilbur J. Crites, Bartlesville, Okla., assignor to
Phillips Petroleum Company, a corporation of
Delaware

Application December 26, 1941, Serial No. 424,539

18 Claims. (Cl. 103—244)

This invention relates to well equipment and more particularly to an apparatus that is adapted for use in wells, including deep hydrocarbon wells.

When a well bore is drilled into a virgin hydrocarbon-bearing formation it is common to find that there is sufficient energy stored in the hydrocarbon fluid to flow that fluid out of the well bore at the surface of the ground. However, as additional wells are drilled into the formation and hydrocarbon fluids are removed therefrom, the energy originally in the formation, unless sustained by a natural water drive or by pressure maintenance methods, becomes depleted and the hydrocarbon oil no longer flows to the surface of the ground. As a great percentage of the hydrocarbon oil still remains in the formation, other means of recovering the oil are employed, such as the utilization of compressed air or gas for gas-lifting the hydrocarbon oil from the lower portion of the well bore to the surface of the ground, or the employment of various mechanical pumping devices. In actual practice in the industry, many wells are equipped with mechanical pumping devices as soon as the wells cease to flow, and many wells, which do not flow naturally when drilled and completed for the production of hydrocarbon oil, are provided with mechanical pumping equipment. This type of equipment may include pumping devices, such as reciprocating pumps which are actuated by a string of sucker rods; submersible, electrically-driven centrifugal pumps; or fluid-actuated pumps.

Present-day types of bottom-hole fluid actuated pumps fall into two general types, one which utilizes a high pressure fluid to actuate a valve mechanism for controlling the pump operation in addition to actuating the pump mechanism, and one which utilizes the rotation of a string of inner tubing from the surface of the ground to actuate the valve mechanism for controlling the pump operation and utilizes the pressure fluid to lift the well fluid to the surface of the ground. It has been found that, when the pressure fluid must actuate both the valve mechanism and the pump, considerable energy is consumed in operating the valve mechanism lowering the operating efficiency of the pump. The rotation of a long string of tubing from the surface of the ground as in the case of the second type of fluid actuated pumps, has several inherent disadvantages: Special equipment, which is required for rotating the inner string of tubing, and the tubing itself are expensive; the rotation of the inner tubing within the outer tubing causes considerable wear on the inner surface of the outer tubing and on the outer

surface of the inner tubing; and the rotation of the inner string of tubing produces appreciable turbulence in the stream of well fluid being conveyed to the surface of the ground. Turbulence is undesirable, especially if the well fluid includes both oil and water whereupon emulsions are formed therefrom necessitating treating.

A fluid displacement pump of the latter mentioned type is disclosed in the patent to Steele 2,202,970. The arrangement shown in this patent includes inner and outer tubing strings, the inner string carrying at its end a plug valve member and chamber in which the oil is accumulated. Pressure gas applied from the surface of the ground provides the lifting power for the oil admitted to the accumulation chamber forcing said oil to the surface through the inner tubing string. In order to allow continuous operation of the fluid displacement pump, the plug valve member is provided, which alternately admits pressure gas to the accumulation chamber to lift the oil and vents the chamber to accommodate a new charge. The plug valve member is operated continuously in the aforesaid patent to provide this action by rotation of the inner tubing string by a motor at the ground surface.

By the practice of my invention I am able to overcome the disadvantages of many types of pumping equipment which are actuated by a high pressure fluid. By withdrawing and thence utilizing a small part of the pressure fluid, my device produces a rotational motion which may be utilized in controlling the admission and exhaust of the pressure fluid within the pumping apparatus. Further, the withdrawal of a small portion of the pressure fluid for actuating my device does not appreciably reduce the pressure of the fluid which is utilized for operating the fluid-actuated pump.

The primary object of my instant invention is to provide an apparatus that is adapted for use in wells, including deep hydrocarbon wells.

Another object of my invention is to provide an apparatus for operating fluid-actuated pumps.

A further object is to provide an apparatus for controlling the admission and exhaust of pressure fluid which is utilized to operate a fluid-actuated pump.

These and additional objects and advantages will be apparent to persons skilled in the art by reference to the following description and annexed drawings wherein,

Figure 1 is an elevation view of my invention partly in cross-section;

Figure 2 is a sectional view of my apparatus, taken along line 2—2 of Figure 1;

Figure 3 is a sectional view of my apparatus, taken along line 3—3 of Figure 1; and

Figure 4 is a sectional view of my apparatus, taken along line 4—4 of Figure 1.

Figure 5 is a vertical sectional view of the pump apparatus showing the cylinder in position to allow the gas under pressure to enter into the accumulation chamber.

Figure 6 is a transverse sectional view through the pump apparatus taken on the line 6—6, of Figure 5.

Figure 7 is a transverse sectional view through the pump apparatus taken on the line 7—7, of Figure 5.

Figure 8 is a transverse sectional view of the pump set when the pump mechanism is removed, taken on the line 8—8, of Figure 3.

Referring to the drawings, and more particularly to Figure 1, I have denoted therein a lower cylindrical housing or adapter tube by reference numeral 10. Housing 10, which is adapted to be lowered into a well bore, is provided with an interior flange 11, having a plurality of substantially vertical passages 12, a circular passage 13, and a plurality of radial ports 14 which provide communication between the circular passage 13 and the exterior of housing 10. Housing 10 is secured at the top to an outer oil well tubing 15, by which my apparatus is supported in the well bore from the surface of the ground in a known manner. The lower end of housing is secured to a pump barrel 16 which contains a pump mechanism 17, having an upper rotatable tubular member 18. An example of this type of pump mechanism is disclosed in United States Patent No. 2,202,970, which issued to F. E. Steele. A cylinder 19, having a plurality of sealing rings 20 arranged on its outer surface, is adapted to be positioned in housing 10, in a manner whereby rings 20 are in sealing engagement with the inner surface of flange 11. Cylinder 19 consists of a centrally bored member 21, having an inlet opening 22 and an outlet opening 23 which communicates with passage 13; a cap 24, which is threadedly connected to the upper end of member 21 and which is preferably provided with a hexagonal opening 25; the cap 24 having internal screw threads by which it is adapted at the top to connect with an inner string of well tubing 26 that extends upwardly to the surface of the ground where it is supported in a known manner; a hollow cylinder 27 which is threadedly connected to the lower end of member 21; and a centrally bored base member 28 which is threadedly connected to the lower end of cylinder 27. It is to be noted that a non-rotating stem 29, having a central passage 30, is adapted to reciprocate through opening 25. Although the upper portion of stem 29 is preferably the same cross-sectional shape as opening 25 in order to allow reciprocation without rotation of the stem, the lower portion thereof is preferably circular in cross-section in order to make threaded connection with a reciprocable hollow piston 31 that is contained in member 21. A spring chamber 32, which is formed interior to member 21 and exterior to stem 29 between the upper end of piston 31 and the lower end of cap 24, contains a compression spring 33 of any desired strength. A hollow rotatable shaft 34 having a groove 35 formed thereabout is slidably contained within hollow piston 31. The groove which is adapted to receive a guide pin 36 that is removably positioned in piston 31, may be of any desired shape that permits pin 36 to impart a rotational movement to shaft 34

as piston 31 reciprocates with respect to member 21. The lower end of shaft 34 is secured to a rotatable connector tube 37 which is in slidable contact with the lower portion of piston 31. Tube 37 is threadedly connected to the lower end portion 38 of a rotatable sleeve valve 39. A pressure fluid chamber 40 is formed exterior to the lower part of tube 37 and interior to the upper part of sleeve valve 39 between the lower end portion 38 of the valve and the lower end of piston 31. Chamber 40 communicates through a plurality of inlet ports 41, and opening 22 with an annular space 42, which is formed interior to tubing 15 and which extends downwardly from the surface of the ground. For purposes of this invention, annular space 42 is to be understood as that annular space extending downwardly to the top of flange 11. Sleeve valve 39 is also provided with a plurality of discharge ports 43 which provide communication between chamber 40 and opening 23. It is to be noted that ports 41 and 43, each of which is illustrated by a plurality of small openings, may be formed by a pair of single openings extending over half of the circumference of sleeve valve 39 and that ports 41 and 43 are disposed on opposite sides of the sleeve valve, preferably at different levels. The lower end portion 38 of valve 39 is also adapted to connect with a hollow timing shaft 44, which extends downwardly to connect with tubular member 18. It is to be noted that communication is provided between pump 17 and tubing 26 by way of member 18, timing shaft 44, tube 37, hollow shaft 34, passage 30, and opening 25. The lower end of the timing shaft is provided with a suitable bearing 45 which is positioned in base 28 by a threaded ring 46 to prevent vertical movement of shaft 44, sleeve valve 39, tube 37, and shaft 34. The timing shaft is provided with a gear 47 which meshes with a pinion 48 that is carried on a spindle 49. Spindle 49 is rotatably positioned between member 21 and base 28 within a chamber 50 that is formed interior to cylinder 27 and exterior to shaft 44. A conventional type of escapement mechanism 51, which is contained in chamber 50 and which controls the reciprocation of piston 31 by controlling the rotation of shaft 44 through the cooperation of pinion 48 and gear 47, consists of: A balance wheel 52, which is carried on a second spindle 53 that is pivotally mounted between member 21 and base 28; a flexible spring 54 which is connected to the lower end of member 21 and to spindle 53; an escapement lever 55 which is adapted to engage with a pin 56 that is supported on balance wheel 52 and which is mounted on a third spindle 57 that is also pivotally mounted between member 21 and base 28; and a pallet 58 which is also mounted on spindle 57 and which is adapted to engage with a ratchet wheel 59 that is carried on spindle 49. It is to be noted that a gas receiving chamber 60, which communicates with annular space 42 by way of passages 12, is formed below the lower face of flange 11 between the interior surface of housing 10 and the exterior surface of cylinder 19. For purposes of this description, chamber 60 extends downwardly within barrel 16, communicating with the interior of pump mechanism 17. The casing 16 extends down into the well hole 124 and has the bull plug or protecting device 125 mounted thereon which contacts the bottom of the well and serves to protect the standing valve 126 from the mud or accumulations of sand in the bottom of the hole. Above the standing valve

128 is a space 127 which is the accumulation chamber when the pump mechanism is mounted in the well. Extending inwardly from the tubing string 16 and at the top of the accumulation chamber is a flange 128 which has a seat portion to receive the pump mechanism 130 when lowered within the outer tubing 16. The flange 128 has a channel or outlet portion 139 therethrough which passage communicates with the space between the casing and outer tubing 16.

The flange or projection 150 on the seat 128 aligns the barrel 132 when placed on the seat 128 and insures against rotation of the barrel if the plug should become stuck to the barrel.

Mounted on the end of the tubular member 18 by means of screw threads 131 is the pump mechanism 130 which has a portion on the end thereof to seat and seal with the seat 128 on the flange in the outer string of tubing 16. The pump mechanism 130 is made up of an outer cylindrical member or barrel 132 which has the inner cylindrical plug member 133 rotatably mounted therein. The two members 132 and 133 are held in assembled relation by the screw thimble 134 which is attached by the screw threads 135 to the outer cylindrical member or barrel 132 and the shoulder portion of the thimble contacts the upper end of the plug to hold the same assembled in the member 132. Bearings 136 are mounted in the space 137 in the thimble 134 to relieve friction and add support to the inner tubing 112 when the tubing is rotated.

In the side wall of the member 132 is the passage 140 which communicates with the passage 113 and the passage 141 in the plug member 133. The member 132 has the passage 142 in the opposite side from the passage 140, which communicates with the passage 140 through the passage 141 in the plug member when the passages are aligned as shown in Figure 6. Passage 143 extends vertically through the member 132 and terminates in the lower end of the member 132, thus establishing communication between the accumulation chamber and the space 113 when the plug is in the position shown in Figure 5. In the lower end of the member 132 is the branch passage 144 which connects with the passage 143 to establish communication through the passage 145 in the plug, passage 146 in the lower end of the member 132 and thence through passage 129 in the seat portion to the space 114 to exhaust the pressure gas from the accumulation chamber when the plug is in the other position.

The plug member has a central passage 149 extending the length of the plug and a nipple 147 projecting into the accumulation chamber with a check valve 148 therein, to conduct the flow of oil from the accumulation chamber 127 to member 18 and then to the surface of the ground. The check valve 148 prevents flow of oil from the member 18 back into the accumulation chamber.

It is noted that the plug 133 is cut away around the openings 141 and 145 so that the ports 141 and 145 are closed for only a very short period of the rotation of the plug.

In operation, the apparatus is assembled as shown in the drawings, and positioned in a well bore from which pump mechanism 17 causes fluid therein to be urged upwardly to the surface of the ground. Let us assume that a pressure fluid which is utilized in actuating my instant apparatus is conducted to the interior of the pump mechanism by way of annular space 42, vertical passages 12, and chamber 60, where the pressure fluid is utilized to lift well fluid from the interior of the pump upwardly through tubular member

18, hollow timing shaft 44, rotatable tube 37, hollow driving shafting 34, passage 38, opening 25, and thence through tubing 26 to the surface of the ground. During the operation of the pumping mechanism, the admission of pressure fluid to the interior of the mechanism and the exhaust therefrom are controlled by a known means within the pump mechanism which is actuated by the rotation of tubular member 18.

10 The pump operation will not be described as it is the same as in the patent to Steele No. 2,202,970.

Referring to the drawings, piston 31 is shown as beginning its upward stroke. Part of the pressure fluid in annular space 42 flows through opening 22, inlet ports 41 and thence into chamber 40 where the fluid acting upon the lower surface of hollow piston 31 urges the piston upwardly against the action of spring 33. As stem 29 is reciprocable and non-rotatable through opening 25,

20 piston 31 is prevented from rotating during its upward and downward strokes, thus allowing pin 36 to reciprocate in a substantially vertical manner. As shaft 34, sleeve valve 39 and timing shaft 44 are connected together forming a rotatable unit, bearing 45 permits rotational movement, but prevents vertical movement thereof. Therefore, as piston 31 moves upwardly, pin 36 causes shaft 34 to rotate. The rotation of shaft 34, by rotating sleeve valve 39 therewith, permits pressure fluid to enter chamber 40 through ports 41 continuously during the upward stroke of piston 31.

25 When the piston completes the upward stroke, shaft 34 and sleeve valve 39 will have been rotated through an angle of 180 degrees, closing inlet port 41 and opening exhaust ports 43. The upward stroke of the piston also compresses spring 33. Thus, pressure fluid is prevented from entering chamber 40; fluid already in the chamber is exhausted therefrom through ports 43, outlet opening 23, circular passage 13, and thence through radial ports 14 to the exterior of my instant device; and compression spring 33 urges piston 31 downwardly through its downward stroke. When piston 31 has completed its downward stroke, sleeve valve 39 has rotated through another angle of 180 degrees, closing ports 43 and opening ports 41 whereupon the pressure fluid again enters chamber 40 and urges piston 31 upwardly to repeat the cycle. It will be apparent

30 that due to varying loads, shaft 34 would rotate at varying rates of speed causing pump mechanism 17 to operate irregularly, unless some type of regulating means, such as escapement 51, were employed to produce a constant rotational speed of shaft 34. With the arrangement of ports 41 and 43 as shown in the drawings, shaft 34, tube 37, sleeve valve 39, timing shaft 44 and tubular member 18, are arranged to rotate in a clockwise direction. Thus, gear 47, which is secured to

35 timing shaft 44, rotates pinion 48, spindle 49, and ratchet gear 59 in a counterclockwise direction. The upward stroke of the piston also compresses spring 33. Thus, pressure fluid is prevented from entering chamber 40; fluid already in the chamber is exhausted therefrom through ports 43, outlet opening 23, circular passage 13, and thence through radial ports 14 to the exterior of my instant device; and compression spring 33 urges piston 31 downwardly through its downward stroke. When piston 31 has completed its downward stroke, sleeve valve 39 has rotated through another angle of 180 degrees, closing ports 43 and opening ports 41 whereupon the pressure fluid again enters chamber 40 and urges piston 31 upwardly to repeat the cycle. It will be apparent

40 that due to varying loads, shaft 34 would rotate at varying rates of speed causing pump mechanism 17 to operate irregularly, unless some type of regulating means, such as escapement 51, were employed to produce a constant rotational speed of shaft 34. With the arrangement of ports 41 and 43 as shown in the drawings, shaft 34, tube 37, sleeve valve 39, timing shaft 44 and tubular member 18, are arranged to rotate in a clockwise direction. Thus, gear 47, which is secured to timing shaft 44, rotates pinion 48, spindle 49, and ratchet gear 59 in a counterclockwise direction.

45 As ratchet gear 59 rotates in a counterclockwise direction, first one tooth of pallet 58 and then the other engages with the teeth of the ratchet wheel 59, permitting one tooth at a time to escape from the pallet. The oscillation of the pallet is controlled by escapement lever 55 that is carried on spindle 51. The escapement lever is caused to oscillate by pin 56 which engages with the free end of the escapement lever for a short interval

50 of time during the oscillation of balance wheel 52. The oscillation of the balance wheel is caused by the coiling and uncoiling of flexible spring 54. It will be apparent to persons skilled in the art that the rotational speed of timing shaft 44 is controlled by the degree to which spring 54 is

coiled or wound. Spring 54 may be loosely wound, whereby balance wheel 52 will oscillate slowly, causing lever 55 to oscillate slowly, which in turn permits only a few teeth of the ratchet wheel to escape from pallet 58 during a given unit of time, causing timing shaft 44 to rotate slowly. On the other hand, if spring 54 is tightly wound, balance wheel 52 oscillates rapidly, permitting timing shaft 44 to rotate rapidly.

It is to be noted that, although I have described my instant invention with reference to its adaptation for use in conjunction with deep well pumps, I do not desire to limit the application of my device to this use alone, and further that my instant invention may be advantageously employed as remote control apparatus in many other types of fluid operated equipment.

Although the invention has been herein shown and described in simple and practicable form, it is recognized that certain parts or elements thereof are representative of other parts or elements which may be used in substantially the same manner to accomplish substantially the same results. Therefore, it is to be understood that the invention is not to be limited to the exact details described herein, but is to be accorded the full scope and protection of the following claims.

I claim:

1. In a well pumping apparatus, the combination comprising a fluid displacement pump, a conduit for transmitting pressure fluid to said pump, a rotatable member controlling the admission of said pressure fluid to said pump, means responsive to said pressure fluid for imparting rotation to said member and escapement timing means for controlling the periodic admission of pressure fluid to the first mentioned means.

2. In a well pumping apparatus the combination comprising a fluid displacement pump provided with a fluid inlet and a fluid outlet, an inner conduit in the well bore for transmitting fluid from the pump outlet to the surface of the ground, an outer conduit in the well bore and spaced from the inner conduit to form an annular passage through which pressure fluid is transmitted downwardly to the pump, means located entirely adjacent the pump and associated with the inner conduit and adapted to control the admission of said pressure fluid to the pump, said means being responsive to pressure fluid that is periodically admitted thereto from the annular passage, and means for controlling the periodic admission of said pressure fluid to the first mentioned means.

3. In a well pumping apparatus the combination comprising a fluid displacement pump, an inner conduit in the well bore for transmitting fluid from the pump outlet to the surface of the ground, an outer conduit in the well bore and spaced from the inner conduit to form an annular passage through which pressure fluid is transmitted downwardly, a fluid motor adjacent the pump operating a valve, the valve being associated with the inner conduit for controlling the admission of pressure fluid to the well pump and means for controlling the periodic admission of pressure fluid in the fluid motor.

4. In a well pumping apparatus the combination comprising a fluid displacement pump provided with a fluid inlet and a fluid outlet, an inner conduit in the well bore for transmitting fluid from the pump outlet to the surface of the ground, an outer conduit in the well bore and spaced from the inner conduit to form an annular passage through which pressure fluid is trans-

mitted downwardly, a fluid motor adjacent the pump operating a valve, the valve being associated with the inner conduit for controlling the admission of pressure fluid to the pump and an escapement mechanism for controlling the periodic admission of pressure fluid to the fluid motor.

5. In a well pumping apparatus disposed in a well bore the combination comprising a fluid displacement pump having a fluid inlet and a fluid outlet, a first valve in the pump controlling the admission of pressure fluid to the pump, an inner conduit in the well bore for transmitting fluid from the pump outlet to the surface of the ground, an outer conduit in the well bore and spaced from the inner conduit to form an annular passage through which pressure fluid is transmitted downwardly, means associated with the inner conduit including a cylinder, said cylinder having a passage providing communication between the interior of the cylinder and the annular passage, said cylinder having a second passage in communication with the interior of the outer conduit, second valve means for controlling the transmission of fluid through both of said passages, a reciprocable piston within the cylinder, a shaft secured to the first valve and forming part of the inner conduit operably connected to the piston and adapted to be rotated by the reciprocation of the piston for controlling by means of the first valve the admission of pressure fluid to the pump, and means for controlling the period of valve actuation.

6. In a well pumping apparatus the combination comprising a fluid displacement pump having a fluid inlet and a fluid outlet, a first valve controlling admission of pressure fluid to the pump, an inner conduit in the well bore for transmitting fluid from the pump outlet to the surface of the ground, an outer conduit in the well bore spaced from the inner conduit to form an annular passage through which pressure fluid is transmitted downwardly, means associated with the inner conduit, said means including a cylinder, a reciprocable piston within the cylinder, a closed chamber within the cylinder, said piston closing one end of the chamber, said cylinder having a passage providing communication between said chamber and the annular passage, said cylinder having a second passage providing communication between the chamber and the exterior of the outer conduit, second valve means for controlling the transmission of fluid through both of said passages, a shaft operating said first valve and forming a continuation of the inner conduit rotatable upon reciprocation of the piston and means for controlling the period of valve actuation.

7. In a well pumping apparatus the combination comprising a fluid displacement pump having a fluid inlet and a fluid outlet, a first valve controlling admission of pressure fluid to the pump, an inner conduit in the well bore transmitting fluid from the pump outlet to the surface of the ground, an outer conduit in the well bore spaced from the inner conduit to form an annular passage through which pressure fluid is transmitted downwardly, means associated with the inner conduit, said means including a cylinder, a reciprocable piston within the cylinder, guide means for preventing rotation of the piston, a closed chamber within the cylinder, said piston closing one end of the chamber, said cylinder having a passage providing communication between the chamber and the annular pas-

sage, said cylinder having a second passage providing communication between the chamber and the exterior of the outer conduit, second valve means for controlling the transmission of fluid through both of said passages, a shaft forming a continuation of the inner conduit connected with and operating the first valve for controlling admission of pressure fluid to the pump, said shaft being adapted to rotate upon reciprocation of the piston, and means for controlling the period of valve actuation.

8. In a well pumping apparatus the combination comprising a fluid displacement pump having a fluid inlet and a fluid outlet, a first valve controlling admission of pressure fluid to the pump, an inner conduit in the well bore for transmitting fluid from the pump outlet to the surface of the ground, an outer conduit in the well bore and spaced from the inner conduit to form an annular passage through which fluid pressure is transmitted downwardly, means associated with the inner conduit, said means including a cylinder, a reciprocable piston within the cylinder, guide means for preventing rotation of the piston, a closed chamber within the cylinder, said piston closing one end of the chamber, said cylinder having a passage providing communication between the chamber and the annular passage, said cylinder having a second passage in the cylinder providing communication between the chamber and the exterior of the outer conduit, a shaft forming a continuation of the inner conduit operably connected to the piston and adapted to be rotated upon reciprocation of the piston, said inner conduit being connected to the first valve for controlling admission of pressure fluid to the pump, second valve means for controlling the transmission of fluid through both of said passages, said second valve means being actuated by rotation of said shaft, and means for controlling the period of valve actuation.

9. In a well pumping apparatus the combination comprising a fluid displacement pump having a fluid inlet and a fluid outlet, a first valve controlling admission of pressure fluid to the pump, an inner conduit in the well bore for transmitting fluid from the pump outlet to the surface of the ground, an outer conduit in the well bore and spaced from the inner conduit to form an annular passage through which pressure fluid is transmitted downwardly, means associated with the inner conduit, said means including a cylinder, a reciprocable piston within the cylinder, guide means for preventing rotation of the piston, spring means associated with the piston, a closed chamber within the cylinder, said piston closing one end of the chamber, said cylinder having a passage providing communication between the chamber and the annular passage, said cylinder having a second passage providing communication between the chamber and the exterior of the outer conduit, a shaft operably connected with the piston forming a continuation of the inner conduit, said shaft controlling the first valve to control admission of pressure fluid to the pump and rotatable upon reciprocation of the piston, second valve means for controlling the transmission of fluid through both of said passages, said second valve means being actuated by the rotation of the shaft and means for controlling the period of valve actuation.

10. In a well pumping apparatus the combination comprising a fluid displacement pump having a fluid inlet and a fluid outlet, a first valve controlling admission of pressure fluid to the

pump, an inner conduit in the well bore for transmitting fluid from the pump outlet to the surface of the ground, an outer conduit in the well bore and spaced from the inner conduit to form an annular passage through which pressure fluid is transmitted downwardly, means associated with the inner conduit, said means including a cylinder, a reciprocable piston within the cylinder, guide means for preventing rotation of the piston, spring means associated with the piston, a closed chamber within the cylinder, said piston closing one end of the chamber, said cylinder having a passage providing communication between the chamber and the annular passage, said cylinder having a second passage providing communication between the chamber and the exterior of the outer conduit, a shaft forming a continuation of the inner conduit having one end operably connected to the piston rotatable upon reciprocation of the piston, the opposite end of said shaft being connected with the first valve to control the admission of pressure fluid to the pump, second valve means actuated by the rotation of the shaft for controlling the transmission of fluid through both of said mentioned passages in the cylinder, and an escapement mechanism for controlling the period of valve actuation.

11. In a well pumping apparatus the combination comprising a fluid displacement pump having a fluid inlet and a fluid outlet, an inner conduit in the well bore for transmitting fluid from the pump outlet to the surface of the ground, an outer conduit in the well bore and spaced from the inner conduit to form an annular passage through which pressure fluid is transmitted downwardly, means associated with the inner conduit, said means including a cylinder, a reciprocable piston within the cylinder, guide means for preventing rotation of the piston, spring means associated with the piston, a closed chamber within the cylinder, said piston closing one end of the chamber, said cylinder having a passage providing communication between the chamber and the annular passage, said cylinder having a second passage providing communication between the chamber and the exterior of the outer conduit, a shaft operably connected with the piston forming a continuation of the inner conduit, said shaft controlling said first valve and thereby admission of pressure fluid to the pump, said shaft being rotatable upon reciprocation of the piston, second valve means actuated by the rotation of said shaft for periodically controlling the transmission of fluid into and out of the chamber, and an escapement mechanism associated with the shaft for controlling the period of valve actuation.

12. In a deep-well fluid-displacement pump, the combination comprising a stationary casing, a stationary tubing, a pump connected to the casing and tubing, the space between the casing and tubing and the space inside the tubing forming two separate conduits, one of these conduits being means to supply a pressure fluid to the pump and the other conduit being means to carry away the discharge of the pump, valve means in the pump for controlling the admission of said pressure fluid to the pump and fluid motor means having connections from said pressure fluid and exhausting into said discharge conduit for operating said valve means, said motor means and said connections being located entirely adjacent said pump.

13. In a deep-well fluid-displacement pump, the combination comprising a stationary casing,

a stationary tubing, a pump connected to the casing and tubing, the space between the casing and tubing and the space inside the tubing forming two separate conduits, one of these conduits being means to supply a pressure fluid to the pump and the other conduit being means to carry away the discharge of the pump, valve means in the pump for controlling the admission of said pressure fluid to the pump, means located entirely adjacent said pump for operating said valve means and time controlled means governing the speed of operation of said valve means.

14. In a deep-well fluid-displacement pump, the combination comprising a stationary casing, a stationary tubing, a pump connected to the casing and tubing, the space between the casing and tubing and the space inside the tubing forming two separate conduits, one of these conduits being means to supply a pressure fluid to the pump and the other conduit being means to carry away the discharge of the pump, valve means in the pump for controlling the admission of said pressure fluid to the pump, fluid motor means located adjacent said pump for operating said valve means and time controlled means governing the speed of operation of said valve means.

15. In a deep-well fluid-displacement pump, the combination comprising a stationary casing, a stationary tubing, a pump connected to the casing and tubing, the space between the casing and tubing forming two separate conduits, one of these conduits being means to supply a pressure fluid to the pump and the other conduit being means to carry away the discharge of the pump, valve means in the pump for controlling the admission of said pressure fluid to the pump, fluid motor means located adjacent said pump for operating said valve means and time controlled means governing the speed of operation of said valve means.

16. In a deep-well fluid-displacement pump, the combination comprising a stationary casing, a stationary tubing, a pump connected to the casing and tubing and the space inside the tubing forming two separate conduits, one of these conduits being means to supply a pressure fluid to the pump and the other conduit being means to carry away the discharge of the pump, valve means in the pump for controlling the admission of said pressure fluid to the pump, fluid motor means having connections from said pressure fluid and exhausting into said discharge conduit for operating said valve means, said motor means and said connections being located entirely adjacent said pump and time controlled means governing the speed of operation of said valve means.

17. A fluid-displacement pump assembly comprising in combination a pump, a pressure fluid supply conduit and a discharge conduit connected to the pump, a rotary valve in the pump controlling the admission of the pressure fluid to the pump, and a fluid motor also connected to said pressure fluid supply conduit and said discharge conduit adjacent said pump, and connected to said rotary valve and operating said valve.

18. In combination with the elements set forth in claim 16, a time controlled mechanism governing the speed of operation of said valve.

19. In combination with the elements set forth in claim 16, valve means for the fluid motor rigidly secured to the rotary valve for rotation therewith at all times.

WILBUR J. CRITES.
